US00D924334S

(12) **United States Design Patent** (10) Patent No.: **US D924,334 S**
Chatterjee et al. (45) Date of Patent: ** *Jul. 6, 2021

(54) **GAMING CONSOLE**

(71) Applicant: **Microsoft Corporation**, Redmond, WA (US)

(72) Inventors: **Monique Chatterjee**, Seattle, WA (US); **Matthew C. Harvey**, Seattle, WA (US); **Austin R. Porter**, Salem, MA (US); **Richard T. Hanks**, Arlington, MA (US)

(73) Assignee: **Microsoft Corporation**, Redmond, WA (US)

(*) Notice: This patent is subject to a terminal disclaimer.

(**) Term: **15 Years**

(21) Appl. No.: **29/704,059**

(22) Filed: **Aug. 30, 2019**

(51) LOC (13) Cl. **21-01**

(52) U.S. Cl.

USPC **D21/332**

CLAIM

The ornamental design for a gaming console, as shown and described.

DESCRIPTION

FIG. 1 is a top front perspective view of a gaming console showing our new design;

FIG. 2 is a bottom front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawings depict portions of the gaming console that form no part of the claimed design.

1 Claim, 8 Drawing Sheets
